[57] CLAIM

The ornamental design for an endoscope holder, as shown and described.

DESCRIPTION

FIG. 1 is a right side elevational view of an endoscope holder showing my new design, the left side being a mirror image of that shown;

FIG. 2 is a front elevational view thereof;

FIG. 3 is a rear elevational view thereof;

FIG. 4 is a top plan view thereof;

FIG. 5 is a bottom plan view thereof;

FIG. 6 is a horizontal cross-sectional view thereof, taken along line 6—6 of FIG. 1;

FIG. 7 is a right side elevational view of an endoscope holder showing a second embodiment of my new design, the left side being a mirror image of that shown;

FIG. 8 is a front elevational view thereof;

FIG. 9 is a fragmentary rear elevational view thereof, the bottom of the tube portion being shown broken-away for convenience of illustration;

FIG. 10 is a top plan view thereof;

FIG. 11 is a horizontal cross-sectional view thereof, taken along line 11—11 of FIG. 7; and,

FIG. 12 is a bottom plan view thereof.
